UNITED STATES PATENT OFFICE.

WILHELM BREIL, OF ESSEN-BREDENEY, GERMANY.

SHAFT LINING.

Application filed August 24, 1921, Serial No. 495,090, and in Germany August 29, 1919. Renewed January 11, 1927.

(GRANTED UNDER THE PROVISIONS OF THE ACT OF MARCH 3, 1921, 41 STAT. L, 1313.)

My invention refers to a lining for shafts, constructed of tubbings and concrete, and more especially to a lining intended for shafts built by the freezing process.

5 In order to render such shaft lining entirely impervious to water it should have such dimensions that even before the concrete is inserted, the tubbings are able to withstand the pressure of the rock. In this 10 case the tubing may be rendered watertight after the rock has been thawed whereupon the concrete is inserted after the effect of the freezing has subsided completely.

According to the present invention, the 15 tubbings are formed of concentric rings which are connected together, by means of vertical and horizontal ribs. In order to render the intermediate space between the two shells of the iron lining accessible for 20 rendering it watertight and for inserting the concrete, I prefer making the external ring segment somewhat higher than the inner one. To fill up the space between two superposed sections of tubing rings, a removable 25 intermediate ring, likewise made in sections, may be inserted on the inside.

In the case of tubing sections constructed with double walls, the inner ring segments being lower than the outer ones are 30 preferably made stronger than these latter, in order that in case of the inner filling rings not being inserted, the iron lining shall possess sufficient strength.

As long as the inner filling rings are not 35 inserted the interior of the tubbings is accessible for rendering them watertight and for inserting concrete.

While the lower tubing segments are being fitted, the segments of the internal wall 40 must be kept suspended and for this reason they may be attached to the outer segments of the ring by means of brackets consisting of vertical ribs in which apertures are provided.

45 In the drawings affixed to this specification and forming part thereof a shaft lining embodying my invention is illustrated by way of example,

Fig. 1 being a vertical section, while

50 Fig. 2 is a plan view of an individual tubing segment.

Referring to the drawings, each tubing section consists of an outer ring segment *a*

and an inner, lower ring segment *b* which are connected together by vertical ribs *d* and 55 horizontal ribs *c*, respectively. Suitable apertures are provided in these ribs in order that the inner space to be filled in with concrete, forms an integral whole and that vertical reinforcing bars *e* may be introduced. Between each pair of superposed 60 tubing rings intermediate rings *f* are inserted on the inside which are likewise made in sections.

After the shaft lining has been built up 65 completely of cast tubbings the various intermediate ring sections *f* are removed one after the other in order to render the interior accessible, and are subsequently reinserted. After these ring sections have 70 been removed, the interior is rendered accessible for waterproofing the spaces between the various tubing sections.

The concrete is inserted in stages through the gaps produced in the interior wall by 75 the removal of the intermediate rings *f*.

I claim:

1. In a metallic shaft lining in combination, an inner and an outer concentric ring, 80 an open work connection between said rings, the outer ring being longer in axial direction than the inner one, and a removable intermediate ring adjacent to said inner ring.

2. In a metallic shaft lining in combination, an inner and an outer concentric ring 85 section, an open work connection between said sections, the outer section being longer in axial direction than the inner one, and a removable intermediate ring section adjacent to said inner section. 90

3. In a metallic shaft lining in combination, an inner and an outer concentric ring section, an open work connection between said sections, the outer section being longer 95 in axial direction than the inner one, a removable intermediate ring section adjacent to said inner section and vertical ribs connecting said inner section to the outer one.

4. In a shaft lining in combination, a plurality of superposed outer and inner concentric rings, the outer rings being longer 100 in axial direction than the inner ones and abutting against one another to form a cylinder, an openwork connection between the outer and inner rings, removable intermediate rings filling the gaps between adjoining 105

inner rings and means for interconnecting said superposed rings.

5. In a shaft lining in combination, a plurality of superposed outer and inner concentric ring sections, the outer sections being longer in axial direction than the inner ones and abutting against one another to form a cylinder section, an openwork connection between the outer and inner sections, removable intermediate sections fitting the gaps between adjoining inner sections and means for interconnecting said superposed sections.

6. In a shaft lining in combination, a plurality of superposed outer and inner concentric ring sections, the outer sections being longer in axial direction than the inner ones and abutting against one another to form a cylinder section, horizontal and vertical openwork connection between the outer and inner sections, removable intermediate sections fitting the gaps between adjoining inner sections and means for interconnecting said superposed sections. 15 20

In testimony whereof I affix my signature.

WILHELM BREIL.
